THROTTLE CONTROL MECHANISM

Frank E. Liverance, Jr., Grandville, Mich.

Application January 24, 1935, Serial No. 3,351

10 Claims. (Cl. 123—103)

This invention relates to an automatic throttle control mechanism for use with and application to internal combustion engines, particularly as used on motor vehicles.

5 In the starting of internal combustion engines, such as are used with motor vehicles, it is frequently very desirable that the throttle valve associated with the carburetor shall be partly opened in order that there shall be insurance of 10 a sufficient volume of explosive fuel mixture passed to the engine cylinders. This is particularly true when the engine has stood for any length of time and is at atmospheric temperature, which in the colder periods of the year may be 15 quite low. Even in the seasons of the year when the atmospheric temperature is not exceptionally low it is very desirable that on starting the engine the throttle valve be partially open.

It is common to open the throttle valve by operation 20 of a throttle control lever mounted at the center of the steering wheel. This is frequently forgotten and an attempt made to start the engine with the throttle lever at a position in which the throttle valve is substantially closed and then, 25 when the engine does not readily start, the operator of the car will remember to move the throttle lever in the proper direction to partially open the throttle valve. The amount that the throttle lever may be moved is dependent upon the judgment 30 of the operator. It may be moved so much that the engine on starting will race. This is undesirable. It is much better that a predetermined opening of the throttle valve be automatically insured at the time the engine is to be started.

35 The present invention is directed to providing a simple and thoroughly practical mechanism for providing an insurance that the throttle valve shall be open a desired predetermined amount at the time the engine is started. It is also an object of the invention to provide a means whereby 40 the extent of the throttle valve opening at the time the engine is started may be varied or adjusted for different temperature conditions of different periods of the year. It is a still further object of the invention that, when the engine has started and is operating under its own power, such means for thus partially opening the throttle valve for starting is rendered ineffective so that thereafter the accelerator pedal control of the 45 speed of the engine may be accomplished throughout the entire range of speed, from idling speed to the maximum speed of the engine. And it is a still further object of the invention to provide means whereby, for a short period of time 50 after the engine has started, the release of the

throttle so that it may move to a position to provide idling speed for the engine is gradual and not abrupt, thereby providing an interval of time whereby the operator may move his foot from the starter pedal, depression of which by the foot 5 closes the starting motor circuit, and engage the accelerator pedal before the throttle valve has moved to its closed position. This is desirable for the reason that should the mechanism, which holds the throttle valve partially open when the engine is at rest, immediately become ineffective upon the engine starting, there might be a 10 dying of the engine and its stopping before the accelerator pedal could be engaged for the purpose of maintaining the throttle valve open the 15 necessary amount to insure continuation of the engine running during the period of time after it has started before it becomes warmed up sufficiently to run at idling speed.

An understanding of the invention for the attainment of the above stated objects and purposes, as well as others not at this time specifically enumerated, may be had from the following description, taken in connection with the accompanying drawing, in which,

Fig. 1 is a side elevation, partly in section, illustrating the application of the automatic throttle control to an internal combustion engine, and

Fig. 2 is a central vertical section through a different or modified form of vacuum cylinder which may be used.

Like reference characters refer to like parts in the figures of the drawing.

In motor vehicles, the power plant, an internal combustion engine, indicated at 1, is provided with an intake manifold, as indicated at 2, from which the explosive mixture of air and fuel passing into the manifold from the carburetor 3, is carried to the engine cylinders. The carburetor is provided with a shaft 4 extending through the upper portion of said carburetor, on which the usual throttle valve V is mounted within the carburetor outlet neck as indicated in dotted lines. The valve turning with the shaft 4 may be moved from substantially closed position through different positions until maximum open position is reached. The more the throttle valve is closed the less the volume of fuel mixture which passes to the engine cylinders. Conversely, the more the throttle valve is moved toward open position the greater the volume of fuel mixture which goes to the cylinders. It is by control of this throttle valve, usually through the foot operation of an accelerator pedal that the speed of rotation of the engine 55

crank shaft, and the consequent speed that the vehicle has over the ground, is governed.

An arm 5 is connected at one end to the shaft 4, to the outer end of which, in the illustration shown, one end of a rod 6 is pivotally connected. The opposite end of the rod 6 is connected at the lower front corner of a triangular plate 7 pivotally mounted at 8 at its upper corner in front of and below the usual downwardly and rearwardly inclined footboard 9 of the front or driving compartment of the motor vehicle. A rod 10 is pivotally connected at its lower end to the lower rear corner of the plate 7 and extends through an opening in the footboard 9 and preferably is provided with a head at its upper end, against which an accelerator pedal 11 bears. The pedal is pivotally mounted adjacent its lower end as shown. It is evident that by placing the foot on the pedal 11 and pressing thereon the rod 6 may be moved in a substantially horizontal direction to the left and thus move the throttle valve more and more toward open position. A spring 12 connected at one end to the plate 7 and at the other end to the footboard 9 tends to move the rod 6 and connected parts to the right. This spring 12 may be applied at any place in connection with the mechanism between the accelerator pedal and the throttle valve for the purpose of moving the same in a direction opposite to the direction of movement that pressure upon the accelerator pedal accomplishes. Such mechanism or an equivalent mechanism, for accomplishing the same result is old and well known in connection with motor vehicles, the motive power of which is an internal combustion engine.

A cylinder 13 is pivotally connected at 14 so as to be suitably supported by the engine block. A tube 15 connects the interior of the cylinder at its closed end with the manifold 2. A piston 16 is mounted in the outer end portion of the cylinder between which and the bottom of the cylinder is a coiled compression spring 17. A rod 18 extends from the outer end of the piston and is connected at its outer end to the lower end of a lever 19, pivotally mounted between its ends at 20, and having a fork 21 at its upper end, the legs of which pass one at either side of the rod 6, and the front edges of which bear against the rear side of a collar 22 mounted on the rod 6. Provision is made for adjustably securing the collar 22, as by a set screw connection, so that the collar may be shifted to different positions on the rod 6.

An arc-shaped plate 23, supported on the engine block and with which the pivot 20 may be connected, depends below the pivot 20. At each side of the lever 19 at its lower opposite corners it is formed with stop lugs 24 and 25. An adjusting screw 26 is shown threaded through the lug 25, and it is evident, of course, if desired that a like adjusting screw may be threaded through the lug 24.

Operation

When the engine is at rest, the spring 17 moves the lever 19 in a counterclockwise direction until stopped against the end of the screw 26. The upper forked end 21 of the lever 19 moves the collar 22 and the rod 6 to which it is attached to the left. The spring 17 is strong enough to accomplish this movement and overcome the spring 12. Therefore, the throttle valve is partly opened, the extent of the opening being dependent upon the position of the adjusting screw 26 and the collar 22. It is evident also that the accelerator

pedal which follows the rod 10 is lowered below its extreme upper position and the position which it would occupy if the lever 19 did not thus act upon the rod 6 to move the same against the spring 12. The throttle valve is partly opened and held in a predetermined position such that the volume of fuel mixture, when the engine is being turned over by the starting motor, is greater than it would be if the throttle valve was permitted to move to its extreme closing position. This insures that when the engine is to be started that the throttle valve will be partially open and will not be in the more closely closed position such as it occupies and to which it is ordinarily adjusted for idling.

As soon as the engine starts and is running under its own power there is a lowering of pressure within the manifold 2 below atmospheric pressure, which lowering of pressure is communicated by the tube 15 to the interior of the piston 13. The pressure of air against the outer end of the piston 16, being greater than the pressure within the cylinder 13, causes the piston 16 to move to the left with a compression of the spring 17 and a consequent clockwise turning movement of the lever 19. This releases the rod 6, whereupon spring 12 acts to move the throttle valve to its extreme closed position and cuts down the speed of the engine to idling speed.

There are times when the lowering of pressure within the engine manifold does not occur or, at least, the degree of vacuum is greatly lessened. This occurs at the times when the throttle valve is substantially wide open or is approaching such position. This may occur at very high speeds or at times when the engine is laboring under heavy loads such as going up a steep hill. At such times the spring 17 will move the piston 16 outwardly. There is no effect, however, on the rod 6 because in order to move the throttle valve to or toward its wide open position, the accelerator pedal 11 must have been heavily depressed, thereby moving the collar 22 to the left away from the upper forked end 21 of lever 19 even though such lever should be in the position shown in Fig. 1. As soon as the accelerator pedal 11 is released so as to start the closing movement of the throttle valve the pressure in the manifold again falls below atmospheric pressure whereby, when the collar 22 has moved back to its extreme position to the right, the piston 16 has been moved to the left, and lever 19 brought against the stop 24. Accordingly, during all times when the engine is operating under its own power, the collar 22 and the forked end 21 of the lever 19 do not engage against each other. There is no interference with the free operation of the accelerator pedal between the position which it occupies when the engine is running at its lowest idling speed and the other extreme position wherein the engine is running at its highest speed.

In Fig. 2 a modification in the structure of the cylinder is shown. The cylinder 13a therein is similar to the cylinder 13 and has the same connection of the tube 15 leading from the cylinder to the engine manifold. The piston 16, the spring 17 and piston rod 18 are the same and the rod 18 is to be connected to the lever 19 in the same manner. The cylinder, however, is elongated somewhat and its outer end closed by a plate 27 through which the rod 18 freely passes. The plate 27 has a small air entrance or vent passage 28 therethrough.

At the upper side of the cylinder, a boss 29 is

cast which is interiorly cored or bored, making an enlarged passage through the boss until the wall of the cylinder is reached, whereupon the lower end of said opening in the boss is provided with a downwardly and inwardly inclined tapering seat 30. A smaller passage 31 leads from the larger opening in the boss through the wall of the cylinder. The outer end of the boss is closed by a plug 32 through which are a plurality of air 10 passage or vent openings 33. A ball valve 34 normally rests by gravity on the tapered seat 30 so as to close the passage 31.

It is evident that the outward movement of the piston 16 under the influence of the coiled spring 17 (not shown in Fig. 2) may be more rapid than the inward movement of said piston when the engine starts. On the inward movement of the piston 16 air to fill the space within the cylinder at the right hand end of the piston 20 as it moves to the left can pass thereto only through the small vent 28, other than such small amount of air as may pass around the piston rod 18 through the plate 27. But on the outer movement of the piston 16 the air can pass outwardly 25 not only through the vent at 28, but the pressure will lift the valve 34 for air passage outward through the opening 31 and the several vents at 33.

With such a construction of cylinder and with 30 the piston mounted therein and connected in the same manner as shown in Fig. 1, when the engine starts and there is a consequent tendency of the piston 16 to move immediately to the left to compress the spring 17, the tendency is checked and 35 the piston moves slowly or only as fast as the restricted entrance of air through the passage 28 permits. Therefore, the release of the throttle to move to idling position is gradual. The foot of the operator which depresses the starter pedal 40 is the one which also operates the accelerator pedal. The operator therefore can depress the starter pedal and close the starting motor circuit until the engine starts and, before the fuel volume is cut down with a consequent slowing of speed of the engine to or approaching idling speed, the operator may move his foot to the accelerator pedal and thus not subject the engine to dying down and stopping which might otherwise occur, particularly in the times when 50 the engine is cold. However, when the engine stops or is stopped at the end of a run the piston 16 moves outwardly without appreciable check to its movement and almost instantly positions the throttle valve in its partly open desired position for starting.

The construction described is simple and is very readily and easily applied to the usual rod which is interposed between the accelerator pedal and the throttle valve. It has no parts to get out 60 of order. The adjustment of the collar 22 and of the adjusting screw 26 is very quickly and easily accomplished both being readily accessible for adjustment. There is an insurance that the fuel mixture going to the engine cylinder will be of a predetermined desired volume and not subject to either the forgetfulness of the operator to move the throttle lever mounted at the center of the steering wheel to partly open position, or to an opening of the same haphazardly to a position 65 farther than it should be. The construction is fully automatic in operation under the control of the engine, releasing and becoming ineffective after the engine has started, and immediately operating to become effective when the engine stops.

The detail of structure for accomplishing the same result by substantially the same means may be varied considerably. For example, the cylinder, piston and spring 17 may be replaced by an equivalent diaphragm structure such as is well known in the art in connection with devices operated through vacuum induced by the engine suction. There are many other equivalent devices which will occur to those skilled in the art. Therefore, the invention is not to be restricted to the particular detail of mechanism shown but is to be considered comprehensive of all forms of structure coming within the scope of the appended claims which define the invention. 15

I claim:

1. In an internal combustion engine provided with a carburetor having a throttle means for controlling the volume of fuel mixture passing through the carburetor to the engine, of yielding means acting on said throttle when the engine is at rest, to open the same to a predetermined position to permit a greater passage of fuel mixture than the minimum passage permitted by the carburetor when it is free of said means, and means actuated by air pressure provided through suction of the engine when it is running for releasing said throttle opening means, as and for the purposes specified. 30

2. The combination with an internal combustion engine having a carburetor, throttle means associated with the carburetor for controlling the passage of fuel mixture through the carburetor to the engine cylinders, an accelerator pedal to actuate the throttle means whereby on depression of the accelerator pedal the throttle means is opened, spring means for moving the pedal to upper position and for closing the throttle means to its minimum fuel passage position, a second spring means having greater force than the first spring means operatively connected with the throttle means to partially open the same when the engine is at rest, and engine actuated means operating when the engine is running for releasing the second spring means from effect 45 upon said throttle means. 35

3. In combination with an internal combustion engine having an intake manifold and a carburetor connected with the manifold, throttle means associated with the carburetor for controlling the volume of fuel mixture passing to the engine, an accelerator pedal, interposed means including a longitudinally movable rod between the throttle means and accelerator pedal for operating the throttle means by depression of the accelerator 50 pedal to open the same, spring means for returning the throttle means to its minimum fuel passage position on release of the accelerator pedal, a cylinder, a piston therein, a second spring means acting on the piston to move the same in one direction, means interposed between the piston and said longitudinally movable rod for moving the rod in a direction to partially open the throttle means when the engine is at rest, said second spring means overcoming the first spring 60 means acting on said rod, and a tube connecting the intake manifold and cylinder whereby the piston is moved in opposition to the second spring means thereby releasing the throttle means, accelerator pedal and the means interposed between the two while the engine is running. 65

4. In combination with an internal combustion engine having an intake manifold and a carburetor connected with the manifold, throttle means associated with the carburetor for controlling the 70

- volume of fuel mixture passing to the engine, an accelerator pedal, interposed means including a longitudinal movable rod between the throttle means and the accelerator pedal for opening the throttle means on depression of the accelerator pedal, spring means for returning the throttle means to its minimum fuel passage position on release of the accelerator pedal, a cylinder, a piston therein, a second spring means acting on the piston to move the same in one direction, a collar on the rod, a lever pivotally mounted between its ends, having one end engaging the collar, means connecting the other end of said lever with the piston and stops to limit the pivotal movement of said lever, as and for the purposes specified.
5. In combination with an internal combustion engine having a carburetor provided with a throttle valve, an accelerator pedal, means to operate the throttle valve in one direction by the accelerator pedal, spring means for moving the throttle valve in the opposite direction, a member occupying one position when the engine is at rest, means operated by said member and acting on the throttle valve to partially open the same when said engine is at rest, and means actuated by the operation of the engine when the engine is running for moving the member to another position and thereby releasing the throttle valve from control by said member.
6. In combination with an internal combustion engine having a carburetor provided with throttle means to control the volume of fuel mixture passing through the carburetor to the engine, of means acting when the engine is at rest for moving said throttle means to a predetermined position to increase the quantity of fuel passing to the engine a predetermined amount over the minimum quantity fuel passage at which the carburetor is set, and engine operated means acting when the engine starts in operation, for gradually releasing the throttle means over a short interval of time until said throttle means is entirely released and is free to occupy the position for minimum fuel mixture passage.
7. The combination with an internal combustion engine having an intake manifold, a carburetor connected thereto and a throttle means associated with said carburetor for controlling the fuel passage to the engine, of an accelerator pedal, interposed means including a longitudinally movable rod between the accelerator pedal and throttle for opening the throttle means on depression of the accelerator pedal, yielding means
- normally moving said rod in the opposite direction to close the throttle means, a collar on the rod, a cylinder, a piston therein, a lever pivotally mounted between its ends having one end thereof engaging against a side of the collar, a tube connecting the cylinder and said manifold, connections between the piston and lever whereby on movement of the piston in the cylinder when the engine starts said lever is moved away from said collar, and spring means acting 10 to move said lever against the collar when the engine is at rest, said spring means having strength to overcome said yielding means.
8. In combination with an internal combustion engine having a carburetor provided with a throttle valve, of means for positioning said valve in a predetermined partially open position when the engine is at rest, adjustable means for controlling the extent to which said valve is partially opened when the engine is at rest, and engine 20 operated means acting to release the valve from said first mentioned means when the engine is running.
9. In combination with an internal combustion engine having a carburetor, an intake manifold 25 and a throttle valve between the carburetor and manifold, a shaft on which said valve is mounted for turning movement, an arm extending from the shaft, a rod connected to and extending from said arm, foot operated means for moving said rod in a direction to open the throttle valve, spring means for closing the throttle valve, a collar on the rod, a pivotally mounted lever having one end thereof engaging the collar, means acting 30 on the other end of the lever to press the first mentioned end of the lever against said collar to move the valve to partially open position when the engine is at rest, and a connection between the engine manifold and said lever operating means for turning the lever to release said collar 40 from the action of said lever, when the engine is running.
10. In combination with an internal combustion engine having a carburetor and a throttle means associated with said carburetor for controlling the fuel passage to the engine, of an accelerator pedal for actuating the throttle means, spring means acting on said throttle means when the engine is at rest to lower the accelerator pedal below its extreme upper position, and means operated by the engine when it is running for overcoming said spring means and freeing the throttle means from operation by said spring means.

FRANK E. LIVERANCE, JR.
